UNITED STATES PATENT OFFICE.

GEORGE W. DERR, OF PHILADELPHIA, PENNSYLVANIA.

HERNIAL TRUSS.

SPECIFICATION forming part of Letters Patent No. 698,264, dated April 22, 1902.

Application filed April 16, 1901. Serial No. 56,152. (No model.)

To all whom it may concern:

Be it known that I, GEORGE W. DERR, a citizen of the United States, residing at Philadelphia, in the county of Philadelphia and 5 State of Pennsylvania, have invented new and useful Improvements in Trusses, of which the following is a specification.

This invention is an improved truss comprising a spring-band, preferably of aluminium, having a pad pivoted thereon and pressed in place by means of a spring connected by a link therewith, a light and flexible construction capable of adjustability of action being provided thereby.

15 The characteristics of my invention will more fully appear from the following description, taken in connection with the accompanying drawings, of which—

Figure 1 is a perspective view of a truss 20 made in accordance with my improvements. Fig. 2 is a side elevation, and Fig. 3 is an end elevation, in illustration of my improvements.

As shown in the drawings, the band A, preferably made of aluminium, is formed to fit 25 and clasp the body, a concavity A' being provided to bridge the spinal column, the flexibility and lightness of the material permitting conformation to the body and freedom from undue pressure.

30 The pad B is secured to the lever-arm B L, as by means of the screws b, the lever-arm being oblique to and pivoted upon an arbor a, preferably integral with or made from the body of the band A. The lever has a short

arm B², which is pivoted to a link C, having 35 a pivotal connection on the free end d' of a spring D. The spring D is secured by the adjustable screw d to the band A, the adjustment of the screw regulating the force exerted by the spring and the consequent pressure 40 of the pad B. The arbor a is preferably located at a point near the lower part of the truss-band in order to admit of the operating mechanism, comprising the arm B², the link C, and the spring D, acting within the approximate width of the band, to form a compact 45 structure. The pad B, fixed on the oblique arm B', extends forwardly and when pressed inwardly by the actuating mechanism effects a perfect support.

Having described my invention, I claim—

In a truss, the combination of a spring-band having a pivot or arbor thereon, with a lever having an arm oblique to said arbor, said lever being pivoted on said arbor, a forwardly-extending pad fixed on said oblique arm, a link pivotally connected to said lever, and a spring having one end fixed to said band and the other end pivotally connected to said link, substantially as specified.

In witness whereof I have hereunto set my hand, this 15th day of April, 1901, in the presence of the subscribing witnesses.

GEORGE W. DERR.
